UNITED STATES PATENT OFFICE.

FREDERIC W. ERICKSON, OF LARCHMONT, NEW YORK.

FUSE LOCK.

Application filed January 31, 1928. Serial No. 250,894.

This invention relates to means for ensuring the maintenance of a fuse in an electrical circuit as a protection or safety device in the event that an improper connection 5 has been made to replace an ordinary cutout or fuse plug.

Dangerous conditions exist in many electrical installations when the fuse plugs that are employed for the protection of branch 10 wiring circuits are replaced by persons who are not familiar with the purpose or object of such safety devices. The rules of the fire underwriters limit the size of the fuse plugs in a branch circuit usually to 15 amperes capacity. Similar fuses are obtainable for use on main wires, which fuses are rated at 20, 25 and 30 amperes. Sometimes 15 these larger fuses are improperly inserted to take the places of 15 ampere blown fuses. 20 Furthermore, many electrical fires have occurred and investigations as to the causes have shown that copper cents, metal discs, hair pins and the like have been placed in the plug receptacles of the cutouts in order 25 to reestablish the electrical connections for the circuits, thereby leaving said circuits without any safety fuse protection.

The object of my invention is to provide 30 means for guarding against the existence of such dangerous conditions as above mentioned, by the introduction of a secondary fusible device which is electrically connected to the circuit between the customary accessible fuse and the current-consuming 35 devices.

With the above mentioned object in view, my invention consists in the construction and combination of members substantially as hereinafter described and claimed.

40 Of the accompanying drawings:—

Figure 1 is a plan view, partially diagrammatic, illustrating one embodiment of my invention.

Figure 2 is a side elevation, partly in 45 vertical section, of the chief elements shown in Figure 1.

Figure 3 is a view of my improved fuse lock or secondary members, on a larger scale than Figures 1 and 2, showing the protecting case or sleeve in section and in the 50 position which it may occupy before being slid to locked position.

Figure 4 is an end view and Figure 5 an elevation partly in section, of the secondary 55 fuse case.

Figure 6 is a face or end view of two of

the members which are illustrated at the left of Figure 3.

Figure 7 represents an elevation, partly in section, of the members shown in Figure 6.

Figures 8 and 9 are a side elevation and a face view, respectively, of the locking spring shown in Figure 3.

Figure 10 represents an elevation, partly broken out, of the connecting members shown near the middle of Figure 3.

Similar reference characters designate similar parts or features in all of the views.

In the embodiment chosen for illustration by Figure 1, my improved fuselock is employed in a circuit which includes lamps indicated diagrammatically at 12 and supplied from a source of power not necessary to illustrate through connections including 70 a bus bar 13 and wire 14, and a fusible leg of the circuit which includes wire 15, the fuse-carrying members presently described, a strip or link 16, and bus bar 17.

My improvements include a plurality of, 80 preferably two, fusible elements in series, one being protected by a locking mechanism. For convenience of description and not for purposes of limitation, one will be referred to as the primary fusible link or cutout 85 which may be, as illustrated, a well-known appliance, while the other, which is locked in a case as hereinafter described, will be referred to as the secondary fusible member.

The primary device (Figs. 1 and 2) includes a center or live contact plate 18 suitably connected to the strip 16 and terminating at the base of the insulating socket 19 which contains the usual conducting shell 20, and the plug 21 which contains the fuse 95 link 22, said plug being of the usual structure to effect electrical contact with the shell 20 and the plate 18.

Mounted to electrically connect with the shell 20 is a strip 23 to which the secondary 100 fuse device is connected by a lug 24 and binding screw 25. Said secondary fuse device will now be described.

Referring to Figures 3 and 5, the case 26 has end caps 27, 28, through which extend, 105 respectively, screw studs 29, 30, said studs being at the opposite ends of the fusible wire 31 which, in practice, has a current-carrying capacity sufficiently higher than that of the primary fuse 22 to act as a barrier to protect the circuit from overload if anyone were 110 to make a connection in place of a fused link

22 that would permit of an overload that would endanger the circuit. To illustrate, the primary fuse 22 may be of 15 amperes, and the secondary fuse 31 of 20 amperes.

5 The reason for this will be explained presently.

Mounted on the screw stud 30, and secured by a set screw 32, is a multi-sided nut 33 (Figures 3 and 6), and also mounted on said stud and clamped between said nut 33 and the cap 28, is a disk 34 having a plurality of arms or fingers 35 (Figs. 3, 8 and 9). Said disk and its fingers are preferably made of spring metal such as phosphor bronze or 15 spring steel. At the other end of the nut 33 from the disk 34 is a disk 36 of insulating material. A short length of wire 37, insulated, extends from the lug 24 (Fig. 2) through a central bore in the disk 36 into 20 the central bore of the nut 33, as best illustrated by Figure 7 which is a view looking in a direction opposite to that at the left end of Figure 3. The connection or mounting of said short length of wire 37 is made permanent at both ends in any suitable manner, as by soldering one end in a recess of the lug 24 (Fig. 2) and the other end in the bore of the nut 33 (Fig. 7).

Screwed to the stud 29 (Fig. 5) is a nut 38 (Figs. 3 and 10) having a lug 39 to which the insulated circuit wire 15 is connected as by a binding screw 40.

Before the members described are completely connected, there is slipped onto the 35 wire 15 a protecting case or sleeve 41, preferably made of a frangible substance such as porcelain or glass. Said case or sleeve has a head 42 at one end, an external groove 43 near said head, and an internal conical recess 44. The opening 45 in the head end of the 40 case is of a size to enable the case to be slipped from its relative position illustrated by Figure 3, in the direction of the arrow *a*, over the fuse case 26, until the said opening 45 first passes the spring fingers 35 (compressing them) and finally permits said fingers to spring out into the conical recess 44, thus automatically locking the case 41 in 45 position (Figs. 1 and 2) to protect the secondary fuse 31 in the sense that no access 50 can be had to the case 26 which contains said secondary fuse, unless the frangible case or sleeve 41 is first broken. The groove 43 in the case 41 facilitates such breaking if and when it is necessary to substitute a new secondary fuse for a blown one.

The opening 45 in the head end of the case 41 is multi-sided to correspond with and 55 snugly fit the multi-sided nut 33 when said case is slipped over the locking fingers 35. Since the nut 33 is connected firmly to the wire 37, and when the parts are first assembled is held firmly by the set screw 32 on the stud 30 of the secondary fuse, said nut can 60 not be rotated. Therefore, when the multi-

sided opening 45 is fitted over the nut as just described, there can be no such relative rotation of the members as to effect disconnection of the circuit until after unlocking is effected; and such unlocking first requires 70 breaking of the frangible case 41 as described. Such breaking is required in order to gain access to the case which contains the secondary fuse 31 for the purpose of renewing said fuse. 75

The bore 46 at the other end of the case 41 from its head 42 is but slightly larger than the outside diameter of the insulated wire 15 (Fig. 3), and is elongated sufficiently to prevent access of anything to tamper with 80 the live portion of the electric circuit within the sleeve.

The utility of the structure as a whole is as follows:—

If the normal, accessible, primary fuse is 85 15 amperes or less, and the secondary, locked, fuse is rated at 20 amperes, the circuit has an overload protection of $33\frac{1}{3}\%$ safety factor. If the normal 15 ampere fuse blows repeatedly, it is an indication that there is 90 danger in some appliance, or a defective wire or connection. If then the rules are disregarded, and some improper fuse or other device is used to replace the blown normal member, the secondary member will 95 blow and open the circuit. Current can be restored to the circuit only by breaking the locked case or sleeve 41, and this is to be done by an electrician who will, at the same time, correct the fault that caused the fuse or 100 fuses to blow, and supply proper primary and secondary fuses and a new locking case or sleeve.

Having now described my invention, I 105 claim:—

1. As a protection for an electric circuit having primary and secondary fusible links in series in said circuit, the secondary fuse having a casing provided with a locking member, and a frangible case slidable endwise over the casing of said secondary fuse, said frangible case having a portion to interengage with the said locking member of the 110 said secondary fuse casing.

2. As a protection for an electric circuit which includes primary and secondary fusible links in series, a casing for the secondary fuse, said casing having a locking member, and a frangible case slidable endwise over the secondary fuse casing, said frangible 115 case having a portion to automatically interlock with the locking member of the said secondary fuse casing.

3. Means for protecting an electric circuit which includes primary and secondary fusible links in series, said means comprising a casing for the secondary fuse, and a frangible case enclosing said secondary fuse casing, said frangible case having an internal recess 120 and the secondary fuse casing having spring 125 130

fingers in position to coact with the internal recess of the said frangible case in locking the latter in protecting position.

4. Means for protecting an electric circuit which includes primary and secondary fusible links in series, said means comprising a casing for the secondary fuse, and a frangible case enclosing said secondary fuse casing, said frangible case having an internal recess and the secondary fuse casing having

yieldable means to coact with the internal recess of the said frangible case in locking the latter in protecting position, the frangible case also having a weakened portion to facilitate breakage when access to the secondary fuse is necessary. 15

In testimony whereof I have affixed my signature.

FREDERIC W. ERICKSON.
